APPARATUS FOR REMOTE CONTROL
BOMBING

Delmer S. Fahrney, United States Navy

Application October 24, 1945, Serial No. 624,279

1 Claim. (Cl. 244—3)

(Granted under Title 35, U. S. Code (1952),
sec. 266)

1

My invention relates to a method of and apparatus for bombing by remote control. In accordance with the invention, bombing is accomplished by controlling a glider into a position near, or into collision with, a target and by then causing detonation of an explosive within the glider, destroying both the glider and the target. Apparatus is provided in the glider to perform the following functions: to permit efficient and safe towing by a powered aircraft; to cause the glider to be self-stabilized when in free gliding flight; to permit radio remote control of the glider in free gliding flight; to convey to an operator at a remote point by television an accurate indication of the visible objects in the field of view in front of the glider; and to detonate the explosive charge carried by the glider either upon impact or upon receipt of a signal from the operator.

Using the apparatus mentioned, it is contemplated that in bombing operations the glider will take off in tow behind a powered airplane, will be towed to a position of sufficient altitude and proximity with respect to the target for the target to be within the gliding range of the glider, and will then be released into free gliding flight. The pilot of the powered airplane, or other operator, will thereafter remain in control of the glider through radio remote control, a view of the scene in front of the glider being transmitted by a television transmitter in the glider to a receiver at the remote control point. Gyroscopic stabilizing equipment in the glider maintains it in stable flight, the equipment being so arranged that remote control signals are effective to re-orient the gyroscopes enabling the remote control operator to change the attitude and direction of flight as desired to cause the glider to strike or approach the target viewable by the operator in the picture tube of the television receiver. The operator may, by remote control, detonate the explosive in the glider as it flies near the target; but if not so detonated, an impact switch causes detonation whenever the glider collides with the target.

An object of my invention is to provide apparatus by which a target may be accurately bombed without danger to the controlling personnel from enemy action.

Another object of my invention is to provide a pilotless glider adapted to carry an explosive charge which may be suitably controlled while in tow and while in free gliding flight, and from which will be transmitted a picture of the view in front of the glider to permit remote control

to conform with information which would otherwise be available only to an operator in the glider.

Heretofore, flying torpedoes and various types of bombs have been suggested which were adapted for carrying by parent airplanes and some of which were adapted to remote control. None of these devices have met with any practical success except for use in the indiscriminate bombing of large areas when accuracy was unimportant. The device according to my invention overcomes difficulties inherent in former devices in that the operator who may be far removed from the glider and target is in constant possession of the information essential to accuracy of the operation; that is, he witnesses an exact reproduction of the view in front of the glider. He is at all times certain of the course of the glider, though both glider and target may be completely obscured from him by distance, clouds, or the like. Another most important advantage of my device, and the bombing method made possible by it, lies in the fact that a relatively heavy bomb load may be rapidly transported to the area of the target by an aircraft not adapted to carrying bombs or other loads, as for instance, a fighter airplane. Apparatus hitherto known has not been capable of this type of operation without considerable modification of the parent aircraft. In using my invention, it is necessary to provide in the parent aircraft only a simple towing hook near the tail or on the underbody, a television receiver, and a radio transmitter. All of these may be installed readily and will have no adverse effect on the streamlining or normal operation of the airplane. Accordingly, the parent airplane is immediately restored to full effectiveness as a fighter airplane when the glider is released therefrom for free gliding flight.

The glider according to my invention may be of a standard mass-production type available in quantity. The towing aircraft may be of any type powerful enough to tow a glider. A minimum of expensive, time-consuming alteration is required in the towing aircraft and glider used in my invention. The operation may be carried out readily by pilots with little special training and without danger to the pilot or other personnel or equipment.

Other advantages and objects of the invention will appear from the following description taken in conjunction with the drawings, in which:

Fig. 1 is a side elevation showing the normal relative position of a towing aircraft and towed glider in flight;

Fig. 2 is a side elevation showing the parent

aircraft, glider, and target as they might appear after release of the glider from tow;

Fig. 3 is a diagrammatic view illustrating the major portion of a control system applicable to the glider of my invention; and

Fig. 4 is a diagrammatic view illustrating the radio remote control receiving system of the glider.

Fig. 1 shows glider 1 in flight under tow through towing cable 2 by powered aircraft 3. A rod or feeler 15 is mounted to the glider by a universal joint near the point of attachment of the towing cable, being held in contact at its forward end or tip with the towing cable. In the preferred relative position of the glider and powered aircraft, the towing cable 2 will remain substantially straight, since the glider will be at a small angle below the horizontal from the towing aircraft, the angle being such that the upward force of the air on the towing cable will be just sufficient to support the towing cable. In practice, this angle has been found to be approximately 9° for a particular size of cable and a given air speed, although changing these or other factors will change the angle. If the glider flies higher or lower than at the desired angle below the towing aircraft, the towing cable will not be supported by the air to the extent necessary to maintain the cable straight. Accordingly, if the glider is relatively too high, the towing cable will sag forward, and if too low will bow upward, between the ends. The feeler 15 following the cable will point above a predetermined preferred direction (which may be approximately 9° as mentioned above) in case the glider is too low, or below the preferred direction if it is too high. Motion in a lateral direction of the feeler will be caused by a lateral misalignment of the glider and towing aircraft. Vertical feeler deflection is made effective through a control system later described in connection with Fig. 3 to cause deflection of glider elevators, and lateral motion is effective to cause deflection of glider ailerons and rudder. The theory of operation of the feeler and the specific construction thereof are more completely described in the copending application of Moulton B. Taylor, Serial No. 592,627, filed May 8, 1945, now Patent No. 2,432,548, entitled Automatic Control.

In Fig. 2, the glider 1 is shown in free gliding flight after release from tow behind parent airplane 3. The glider is shown gliding toward a target such as the ship 141, which is within the field of view, approximately centered along the longitudinal axis or line of flight of the glider as indicated by lines 142, of the television image transmitter tube of the television converter unit 143 mounted toward the nose of the glider. Television transmitter 144 connected to the converter unit 143 feeds a signal comprising scanning and equalizing impulses and the picture components to transmitting antenna 145 for transmission to a receiving antenna 146 and receiver 147 in the parent aircraft. An image of the target is impressed on the screen 148 of the receiver cathode ray tube which may be seen by the pilot, giving him the information necessary to proper control of the glider toward the target.

A set of ten switches 151 is provided in the parent airplane to enable the pilot to switch onto the carrier wave generated in a radio transmitter 152 any one or more of ten predetermined modulation frequencies, the modulated carrier being radiated from an antenna 153 to be received on receiving antenna 154 on the glider. The signals

received at the glider are fed to a suitable receiver 155 and control the operation of selected relays dependent upon the modulation frequency. The relays cause operation of certain control apparatus for the glider as will be later described. An explosive charge is indicated in the glider at 156, having an impact detonator.

The control system for the glider is diagrammatically presented in Fig. 3 of the drawings. This system comprises a feeler rod 15 for indicating the position of the towing cable, and cam-operated switching mechanisms controlled thereby through suitable cables for selectively applying electrical energy from a battery 35 to trim and servomotors which deflect control airfoils. These airfoils consist of the usual elevator 48, rudder 178 and aileron 95, and, in addition, a spoiler or airbrake 65. A separate reversible servomotor is provided for the deflection of each of the control airfoils; that is, one for the elevator, one for the rudder, one for the ailerons and one for the spoiler. For clarity, only one aileron is shown, although an oppositely acting second aileron is, of course, provided. The servomotors may be electrically powered, or they may be vacuum or hydraulically powered with electric valves suitably arranged to give right or left rotation as required. Three gyroscopes 171, 184 and 94 are provided for controlling yaw, pitch and roll, respectively. The stabilization axes of these gyroscopes may be changed through operation of trim motors 86 and 161, as later explained. A solenoid actuated double-throw switch 162 is utilized to transfer control from the feeler rod to radio remote control at the time of release of the towing cable.

The operation of the control system while the glider is in tow, in which condition switch 162 will complete a circuit from battery 35 through on-off switch 36 and switch blade 163 to contact 164, is dependent upon feeler rod 15, since power is provided from contact 164 to energize each of the cam-operated switches mechanically connected with the feeler. When the parent aircraft is to the left of the longitudinal axis of the glider, feeler rod 15 is pulled by the towing cable toward the left, moving arm 17 forward, this motion being transmitted through cable 19 to arm 75 connected to cam member 77, both of which are rotatable about an axis 78, the rotation being in the direction to stretch tension spring 79. As cam member 77 rotates about axis 78, switch 82 is closed, providing power from contact 164 through conductor 165 and the switch 82 to conductor 166 and terminal 88 of trim motor 86 to cause arms 85 and 167 of the trim motor to rotate in a direction to effectively shorten cables 90 and 168, which are strung around free-turning pulleys 29 and 169, respectively. This rotation will be in a clockwise direction as shown in the drawing. Current return from trim motor 86, and from each of the other trim and servomotors, is provided through a grounded connection (not shown). The rotation of arm 85, as described, pays out follow-up cable 84 to permit tension spring 83 to rotate flat plate 80 in the direction of rotation in which the cam member 77 was originally rotated. Switches 81 and 82 are mounted on plate 80, and this follow-up rotation is effective to cause the roller 158 of switch 82 to roll off of the raised portion of the cam and again seat against the lower portion, opening switch 82 and removing power from trim motor 86, which thereafter remains stationary until cam 77 is again rotated. The effective shortening of cable 90, as

explained in detail in the aforementioned application entitled Automatic Control, will adjust the stabilization axis of gyroscope 94 by turning pulley 93 through the unwinding therefrom of cable 90, resulting in the closing of switch 99 to provide current from the battery through conductor 101 to conductor 103 and terminal 98 of servomotor 92. The arm 91 of the servomotor moves in a direction to give down right-aileron, or leftward roll control to aileron 95 through cable 96. The motion of arm 91 provides a follow-up action by effectively lengthening cable 90, which rides over free-turning pulleys 118 and 89 to permit slight rewinding of cable 90 on pulley 93 under the influence of spring tension. The stabilization axis of gyroscope 94 is thereby returned toward neutral position, causing switch 99 to center and remove power from servomotor 92. Simultaneously, cable 168 has unwound from reel 170 of directional gyroscope 171 due to motion of arm 167 of trim motor 86, changing the stabilization axis of this gyroscope in a manner similar to that in which roll gyroscope 94 is affected. Switch 172 is closed in the direction to provide power from the battery through conductor 173 and through the switch to terminal 174 of servomotor 175. Arm 177 rotates in a direction shown as clockwise in the drawing to deflect rudder 178 to the left turn position through cable 179. Follow-up cable 168 is effectively lengthened by the motion of the rudder, running around free-turning pulleys 181, 182 and 169 to permit rewinding on pulley 170 returning the stabilization axis toward neutral. The ailerons and rudder retain the deflected positions until the glider has started to respond. As the glider rolls toward the left, the switch 99 of gyroscope 94 closes the battery circuit to terminal 97 of servomotor 92 which causes arm 91 to return aileron 95 toward the neutral or center position. Follow-up of this motion is provided through cable 90 which slightly unwinds from pulley 93 and returns the stabilization axis to a position to again center switch 99 and remove power from the servomotor. Similarly, as the direction of the glider changes, the gyroscope 171 provides power through switch 172 to terminal 176 of servomotor 175 which then returns the rudder toward neutral in the amount necessary to readjust the stabilization axis through unwinding of cable 168 from pulley 170. As the direction of flight of the glider is changed through the combined effects of the deflected rudder and the lateral component of the towing cable pull, the feeler 15 is returned toward the center, and arm 17 moves slightly rearward paying out cable 19, which causes arm 75 to rotate cam 77 into the position to close switch 81 and apply power through conductor 183 to terminal 87 of trim motor 86. The arms 85 and 167 of the trim motor are rotated so as to decrease the prior effective shortening of cables 90 and 168, resetting the gyroscopic system to return the glider toward normal straight flight by action of the trim motor and associated apparatus just described, the actions being now reversed. These automatic adjustments to the control airfoil setting will continue until the longitudinal axis of the glider is directly in line laterally with the towing cable from the parent aircraft. It will be seen that a rightward displacement of the towing aircraft from the straight-ahead position will cause feeler 15 to move to the right of center, paying out cable 19 and setting the trim motor and gyroscopic system for the control of the rudder and ailerons so as to cause rightward yaw and roll of the glider. 75

the sequence of the operations of the control apparatus being the same but in reversed direction.

Vertical displacement of the towing aircraft from the desired angle above the horizontal from the glider will similarly result in the application of suitable correction controls. If the towing aircraft is higher than the preferred relative positions, feeler 15 is raised, paying out cable 18 through the rearward motion of arm 16, allowing tension spring 28 to pull arm 25 in the direction shown as clockwise in Fig. 3 about an axis 27. Cam member 26, pivoted about the same axis, is secured to arm 25 and in response to this motion, rotates in a direction such that roller 33 of switch 30 rides up on raised portion 34 of the cam, closing the switch to provide power through conductor 37 and the switch to conductor 44 and terminal 45 of elevator servomotor 43. Power to terminal 45 is effective to cause arm 46 to pull cable 47 and deflect elevator 48 into an upward or climb position. Follow-up is provided through cable 58 which is effectively lengthened allowing tension spring 51 to rotate plate 31 in the same direction as the original displacement of arm 25. Since plate 31 carries switch 30, the roller 33 will roll off of the raised portion 34, opening switch 30 and taking power off of servomotor 43. Arm 25 carries extending portion 55 to which is connected a control rod 56 through which actuation of spoiler 65 is accomplished. Any upward or downward motion of feeler 15 from the preferred position causes rotation of arms 25 and 55 about pivot 27, and this motion is effective through rod 56 to rotate arm 58 and cam member 57 attached thereto to disengage switch arm 61 from contact 68 and engage contact 66 providing power through conductor 63 to servomotor 64 which is effective through arm 69 and cable 67 to move the spoiler into "on" position. A suitable limit switch (not shown) is provided to disconnect conductor 63 from the servo-motor when the spoiler 65 is in a desired position of maximum displacement. The return of feeler 15 to the preferred vertical position, which may be substantially 9° from the longitudinal axis of the glider in level flight, as previously explained, will be effective to return cam member 57 into the position in which the switch roller engages the lower cam surface, providing current through contact 68 and conductor 62 to servomotor 64 which rotates arm 69 toward the "off" direction returning spoiler 65 to neutral streamlined position. A second limit switch (not shown) may be provided to disconnect conductor 62 from the servomotor when the spoiler has reached neutral to prevent further operation of the servomotor, it being understood that each limit switch is arranged to reconnect conductor 63 and 62, respectively, whenever the spoiler has been moved slightly away from either of the limit positions. These limit switches may be conveniently built into the servomotor 64, and similar limit switching arrangements may be provided in servomotors 43, 92 and 175 to prevent over-control of the elevator, aileron or rudder airfoils, respectively. The purpose of spoiler 65 is to increase the air drag of the glider to pull out of the towing cable any inconsequential bowing of the towing cable to the end that elevator deflection of the glider will be accurately controlled by true deviations from the preferred relative position of the glider with respect to the towing aircraft.

As heretofore mentioned, the glider may be released from the towing cable by radio remote con-

from actuation of a solenoid coil, which, in turn, triggers a releasable connection for the end of the towing cable. Solenoid 189, as shown in Fig. 3, is adapted to trigger a suitable release mechanism upon excitation by pulling cable 185 as the core of the solenoid is sucked in. A suitable coupling, such as insulated cable 180, may be utilized to cause blade 163 of switch 162 to disengage contact 164 and engage contact 160 to provide electric current from battery 35 through switch 36 and switch 162 to conductors 186 and 187 and through them to pitch trim motor 161 and pitch gyroscope 184, and relay contact 188, respectively. It will be apparent that disconnecting contact 164 will make cam-operated switches 29, 30, 81, 82 and 59 ineffective to cause any deflections of the control airfoils. As a result, feeler 15 is completely disabled. Remote radio control is now effective to operate selectively trim motors 86 and 161 as desired. Terminals of switches 20 operated by relays in the output of the radio receiver, later described in conjunction with Fig. 4, are indicated by the numerals 206, 207, 208, 209 and 210, respectively. When the appropriate modulation frequency is received at the glider, a relay is operative to complete a circuit from the ungrounded battery terminal to terminal 206 to excite the coil of solenoid 189 to release the towing cable through tripping cable 185 and to throw switch 162 into the radio control position. Reception of another selected modulation frequency will be effective to connect terminal 207 to the ungrounded terminal of the battery, which will cause rotation of arm 198 of trim motor 161 in the direction to effectively shorten control cable 191. The control cable will be unwound from stabilization-axis-adjusting pulley 192 of pitch gyroscope 184 in a manner similar to that for gyroscopes 94 and 171. Switch blade 193 will immediately engage contact 194, providing current from the battery through conductors 186 and 195 through the switch conductor 196 and conductor 46 to terminal 45 of servomotor 43. The servomotor will rotate in the direction to provide up-elevator control through cable 47. Arm 190 of trim motor 161 will continue to rotate in the direction stated until reception of the particular modulation ceases. Assuming that, as will normally be the case, only a short burst of the modulating frequency has been received, the arm 190 will have moved a short distance. As servomotor arm 46 rotates in the up-elevator direction, cable 191 is paid out over suitable free-turning pulleys and pulley 197 on the trim motor arm to permit slight rewinding on reel 192. Motion of the servomotor arm will thus continue until the elevator has been deflected a sufficient amount to pay out cable 191 to the extent required to set gyroscope 184 and open the contact between blade 193 and contact 194. It will be seen that because of the effective shortening of follow-up cable 191, gyroscope 184 will be operative to maintain the glider in a new pitch attitude by selectively applying additional up-elevator control by closing contact 194, or by applying down-elevator control by closing contact 198, as required to satisfy the system at any moment. This new condition will persist as long as arm 190 remains away from its centered position. When power is removed from terminal 207, by discontinuing the modulation frequency, the trim motor arm 190 is returned to center position by power provided through conductor 186 to centering terminal 159.

Internal cam-operated switches associated with

terminal 159 cause right or left rotation as required until the arm 190 is in a centered position. Of course, the centering control is over-powered by application of current through either terminal 207 or 208. Power to terminal 208 will cause the trim motor to effectively lengthen follow-up cable 191 which will readjust the system to provide an attitude of increased dive. The application of power to terminal 209, through energization of the appropriate remote control relay, is effective to energize terminal 88 of trim motor 86 which will cause effective shortening of cables 90 and 168 of the aileron and rudder control systems. As heretofore discussed, decreasing the effective length of these cables tends to establish a leftward roll and leftward rudder positioning of the glider through the adjustments to the stabilization axes of gyroscopes 94 and 171, respectively. Applying current in response to another modulation frequency to terminal 210 energizes terminal 87 of trim motor 86 to provide rightward roll and rudder setting. Power to terminal 209 will not only energize terminal 88 of trim motor 86 but will also energize relay coil 227 to close a circuit from relay armature 199 to stationary contact 188. Similarly, energization of terminal 210 will, in addition to energizing terminal 87 of the trim motor, energize relay coil 228 to engage armature 222 with stationary contact 221. The closing of either one of the two sets of relay contacts alone has no controlling effect while the other set is open, but simultaneous closing of both sets by the simultaneous transmission of two modulation frequencies to energize both terminals 209 and 210 will result in the completion of a circuit from the battery through switch 36, contact 165 of switch 162, conductor 187, contact 188, armature 199, conductor 220, contact 221, armature 222 and conductors 223 and 224 to a centering terminal 225 on trim motor 86 and caging terminal 226 on gyroscope 171. The trim motor will accordingly operate to a centered position which will remove any bank of the glider, through the action of gyroscope 94, and gyroscope 171 will be caged in the direction of flight of the glider at that time.

Thereafter, the glider will be controlled by the gyroscope 171 to maintain this direction of flight until further signals are received by transmission of appropriate modulation frequencies.

In operation to change the lateral course of the glider, an appropriate modulation frequency is transmitted to energize terminal 209 for a left turn or terminal 210 for a right turn. Trim motor 86 is operated in accordance with this signal to cause yaw and roll in the selected direction and to a degree determined by the length of time the modulation frequency is received. The yaw and roll continues until two modulation frequencies are received simultaneously to energize terminals 209 and 210 together. The gyroscope 171 is then caged, and the trim motor 86 centered to allow the glider to return to even keel, the gyroscope thereafter being operative to maintain the newly established direction of flight. In practice, it will be found necessary to give the centering and caging signal shortly before the glider has reached the desired direction to give enough time for the control to become centered as the glider reaches the desired direction.

The gyroscopes for controlling yaw, pitch and roll in the preferred arrangement are of the type in which air under atmospheric pressure is permitted to enter the cases of the gyroscope to spin the rotors and to operate air pick-off systems which cooperate with suitable Sylphons for actuation of the electric switches. A partial

vacuum is maintained in the case of each gyroscope through the provision of suitable vacuum connections shown in Fig. 3 as 114 for gyroscope 94, 218 for gyroscope 171, and 219 for gyroscope 184. A vacuum Pitot tube (not shown) may be provided to furnish the required vacuum as the glider attains substantial air speed after take-off, or a vacuum pump may be provided in lieu of a Pitot tube to furnish vacuum for the gyroscopes and to power the servomotors if vacuum-operated motors are used. A wind driven generator is provided as shown in Fig. 3 for charging the battery 35 during flight. The arrangement comprises a direct current generator 239 driven by a windmill 231, mounted outside of the glider, through a belt 232. The generator is connected so as to act as a motor at low airspeeds so that it may be used to drive through a mechanical coupling any vacuum or hydraulic pumps (not shown) for required operation of vacuum or hydraulic apparatus in the glider. Airspeed switch 233 is set to remain open until the airspeed of the glider reaches a predetermined amount, which may be approximately 70 miles per hour. Below this speed, power is provided through conductor 234 and manual switch 235 to the generator armature to cause it to run as a motor, field supply being through a suitable resistor 236. Above the predetermined speed, switch 233 closes to energize relay coil 237 to move relay armature 238 away from contact 239 and into engagement with contact 240. This change in connections inserts a voltage regulator 241 into the generator field supply, and thereafter the windmill provides energy to drive the generator as a generator to charge the batteries and to power the vacuum and hydraulic pumps if such pumps are used. Current and speed regulators may be added to the generator system if required under special conditions. It will usually be desirable to include pressure regulating mechanisms (not shown) for vacuum or hydraulic systems.

In Fig. 4 is shown a radio receiver 155 for use in the glider to receive radio signals from the transmitter in the parent aircraft. As heretofore stated, the transmitter is adapted to the transmission of a single radio frequency carrier wave selectively modulated with any one of ten different audible or super-audible modulating frequencies. It is also possible to transmit the carrier modulated with two or more of the ten modulating frequencies. The carrier wave received on antenna 154 is suitably amplified and detected in receiver 155. In the final stage of the receiver are frequency selective circuits suitably coupled to a series of relays, each circuit being tuned to one of the ten modulation frequencies and so coupled as to operate a single relay in response to the reception of the appropriate modulation frequency. In lieu of a coupling arrangement, the actuating coil of each relay may comprise a portion of the tuned or frequency selective circuit on which the operation of the relay is dependent. Upon excitation resulting from reception of one of the modulation frequencies, the appropriate individual relay is operative to close a contact from the ungrounded terminal of battery 35 to one of the terminals 201, 202, 203, 204, 205, 206, 207, 208, 209 and 210. Two or more contacts may be closed simultaneously upon reception of two or more modulation frequencies. When transmission and reception of any modulation frequency is stopped, the individual relay excited by that frequency drops out. Each relay is arranged

to actuate mechanism, such as control mechanism, in the glider. One relay is connected so as to energize in response to one of the modulation frequencies a solenoid coil, 189 in Fig. 3, by supplying battery power to terminal 206, the solenoid being operative to trigger a release catch on the towing cable connecting hook through cable 185 so as to allow the towing cable to pull free of the glider. The ring 20 at the tip of the feeler is also arranged to release the towing cable as the end of the cable is pulled up to the ring. The towing cable connecting hook and the ring on the tip of the feeler are more completely described in the copending application entitled Automatic Control previously mentioned. Certain others of the relays connected into the receiver output circuit are arranged to produce right or left yaw and roll of the glider, or up or down pitch, and to accomplish any desired additional functions, such as to arm or detonate the explosive, or to drop parachute flares. It will be apparent that the pilot at the transmitter, by selecting a particular modulation frequency of the transmitted wave, may cause the towing cable to be released from the glider, and may thereafter produce right or left turn and bank, or dive or climb, of the glider by selecting other frequencies as appropriate.

The apparatus described is particularly adaptable to the accurate bombing of specific targets or small areas from aircraft. The method contemplated by this invention comprises the towing of an explosive-carrying glider by a small powered aircraft, the glider being controlled while in tow by feeler 15 and the associated mechanism shown in Fig. 3. This mechanism is capable of maintaining the glider in a predetermined position relative to the towing aircraft as shown in Fig. 1, despite low visibility, turbulent air, and considerable maneuvering of the towing aircraft. Upon reaching a position with respect to the target from which the glider can be made to glide to the target, the pilot of powered aircraft 3 may transmit by transmitter 152 a signal suitably modulated to close contact 206 in the output circuit of radio receiver 155. As explained in connection with Fig. 3, this will result in the release of the glider from the towing cable and will disable feeler 15 from further glider control. In this condition, the glider will be maintained in a stable flight attitude by the action of the three gyroscopes 94, 171 and 184 and their associated equipment. The towing cable release and disabling of the feeler portion of the control system by the excitation of solenoid 189 is simultaneously operative to energize circuits sensitive to radio remote control of the flight attitude through radio receiver 155. Accordingly, the pilot may select one or more of ten modulation frequencies for transmission, utilizing the bank of switches 151 in Fig. 2 to apply desired modulation frequencies. Accordingly, the attitude of flight of the glider is under the control of the pilot of powered aircraft 3. To enable intelligent and accurate control, television transmitting equipment including converter unit 143, transmitter 144, and antenna 145 on the glider are effective to transmit a signal modulated by suitable impulses to provide on the television receiver screen 148 in the powered aircraft an image of the objects appearing within the field of view in front of the glider shown as being bounded by lines 142 in Fig. 2. It is desirable to launch the glider, as heretofore de-

scribed, after such time as it has been found possible to bring the target, such as vessel 141, within the field of view of the television transmitter tube and to thereafter by radio remote control cause the glider to maintain a collision course with the target. As the glider approaches the target, the image thereof continuously increases in size, increasing the accuracy of the operation. In the meantime, the towing aircraft may have flown away to a safe distance to avoid anti-aircraft fire from the target or other enemy installations, and the glider may be completely obscured from view. However, the accuracy of the operation will not be impaired. A suitable detonator is provided within the glider 15 to cause the explosion of the charge 156 whenever the glider is abruptly stopped, or the charge may be exploded by remote control whenever a particular modulation frequency is transmitted. It may be desirable to explode the charge above 20 the target as, for instance, when scattering incendiary missiles.

The invention may be embodied in other specific forms without departing from the spirit or essential characteristics thereof. The present embodiments are therefore to be considered in all respects as illustrative and not restrictive, the scope of the invention being indicated by the appended claim rather than by the foregoing description, and all changes which come within 30 the meaning and range of equivalency of the claim are therefore intended to be embraced therein.

The invention described herein may be manufactured and used by or for the Government of the United States of America for governmental purposes without the payment of any royalties thereon or therefor.

What is claimed is:

In a towed glider adapted to be controlled directly when towed and to be controlled remotely when in free gliding flight, the combination comprising adjustable control surfaces for controlling the attitude of the glider, means coupled to

5

each of said surfaces for adjusting the position thereof, a towing cable for towing said glider, feeler means coupling said cable to the glider, means responsive to the attitude of said feeler means for actuating said adjusting means to maintain the glider in a predetermined position with respect to said cable when in towed flight, and radio remote control means for actuating said adjusting means independently of said feeler responsive means, said remote control means including means responsive to a predetermined signal from a remote location for simultaneously releasing said tow cable, disabling said feeler responsive means and rendering said remote control means operable to actuate said adjusting means in response to other predetermined signals from said remote location.
